[57] CLAIM

The ornamental design for a lumber drying kiln housing, as shown and described.

DESCRIPTION

FIG. 1 is a perspective view of a lumber drying kiln housing, showing our new design;

FIG. 2 is a front elevational view thereof;

FIG. 3 is a left side elevational view, the right side being

a mirror image thereof;

FIG. 4 is a rear elevational view thereof;

FIG. 5 is a top plan view thereof; and,

FIG. 6 is an enlarged fragmentary perspective view

thereof.
